(57) **CLAIM**

The ornamental design for a multi-edge instrument for treatment of soft tissue, as shown and described.

DESCRIPTION

FIG. 1 is a top perspective view of an embodiment of a multi-edge instrument for treatment of soft tissue showing our new design;

FIG. 2 is a front elevation view thereof;

FIG. 3 is a rear elevation view thereof;

FIG. 4 is a left elevation view thereof;

FIG. 5 is a right elevation view thereof;

FIG. 6 is a top plan view thereof;

FIG. 7 is a bottom plan view thereof; and,

FIG. 8 is a bottom perspective view thereof.

The dashed broken lines shown in FIGS. 1-8 are included for the purpose of illustrating unclaimed portions of the multi-edge instrument for treatment of soft tissue and form no part of the claimed design. The dash-dot broken lines shown in FIGS. 1 and 6-8 are included for the purpose of illustrating boundaries between claimed and unclaimed subject matter, with the dash-dot broken lines themselves being unclaimed subject matter. The relatively light shade lines in FIGS. 1-8 indicate contour and not surface ornamentation.

1 Claim, 4 Drawing Sheets
